UNITED STATES PATENT OFFICE.

WILLARD I. TWOMBLY, OF NEWARK, NEW JERSEY, ASSIGNOR TO ACME ACCESSORIES CORPORATION, OF NEW YORK, N. Y., A CORPORATION OF NEW YORK.

LIQUID-FEEDING MEANS AND PUMP.

Original application filed October 20, 1917, Serial No. 197,589. Divided and this application filed March 25, 1920. Serial No. 368,697.

To all whom it may concern:

Be it known that I, WILLARD I. TWOMBLY, a citizen of the United States, and resident of Newark, in the county of Essex and State 5 of New Jersey, have invented certain new and useful Improvements in Liquid-Feeding Means and Pumps, of which the following is a specification.

This invention relates to means for feeding liquid, as for instance, liquid fuel or gasoline, from a source of supply to a reservoir and to the intake of an engine such as the carburetor of an internal combustion engine.

15 The device as shown herein, is one of several illustrated in my prior application, Serial No. 197,589, filed October 20th, 1917, of which this case is a division.

20 The general purpose of the invention is to provide improved liquid pumping means operable from the movements of the engines, which means are simple and cheap in construction and efficient in operation.

25 Heretofore in apparatus of this character, it has been the practice to connect a reservoir to the intake manifold of an engine and to utilize the suction of the piston of the engine to apply a vacuum directly to the surface of the fuel to draw it from a supply tank to the reservoir, from which it was fed by gravity; also to connect a pump chamber to the cylinder of the engine, the pump being actuated by the suction of the engine during the return or fuel 30 intake stroke of the piston.

35 One object of this invention is to provide means connected directly to the cylinder of the engine and operable by the varying pressures in the engine cylinder, throughout a wide range of varying pressures and speeds of the engine, to draw the fuel from a tank and deliver it to the engine.

40 A further object of the invention is to provide liquid feeding means of this character including a pumping mechanism having a reciprocable piston, said pumping mechanism being interposed between the fuel tank and the engine, the piston of the pumping mechanism operating to separate 45 the pump cylinder into a motive chamber and a pump chamber, the motive chamber being connected to the combustion chamber of the engine and the piston reciprocated

through the varying pressures in the combustion chamber, such as during the power and suction strokes of the engine piston, and the pumping chamber having an inlet connected to the tank and an outlet whereby as the piston is reciprocated liquid is drawn from the tank through the inlet of 60 the pump chamber and delivered from the outlet of the pump chamber.

65 A further object of the invention is to provide means in which the pumping mechanism normally operates to shut off communication between the engine and tank and between the pump and tank, and operable to open communication between the tank and engine when the piston is reciprocated.

70 Another object of the invention is to provide liquid feeding means of this character in which the outlet of the pump chamber is connected and the liquid delivered to a reservoir which is connected to the fuel intake means of the engine, and to provide means whereby the liquid level is controlled 75 and controls the actuation of the pumping mechanism to draw and deliver liquid from the tank.

75 The device shown herein has peculiar advantages as a means serving the above generally stated objects and purposes.

80 The high level reservoir has the pump cylinder located therein and preferably extending therethrough. Preferably, the vessel is cylindrical with the pump cylinder axially disposed therein. Preferably, the pump cylinder is vertically arranged and preferably the intake for the liquid is at 85 the lower end of the cylinder and reservoir while the conduit for application of pressure from the combustion chamber of the engine is at the upper end of said pump cylinder and vessel. Preferably the pump cylinder is rigidly secured water-tight through the bottom of the reservoir and its upper end projects through and serves as securing means for clamping the cover or closure for said vessel.

85 90 95 100 Other objects and advantages will herein after appear.

In the drawings accompanying and forming a part of this specification, Figure 1 is a diagrammatic view showing an embodiment of my invention applied to a motor 105

vehicle utilized to lift gasoline from a tank and deliver it to the carburetor of an engine, the tank being located at a point below the carburetor.

5 Figure 2 is a sectional side elevation of an embodiment of a pumping mechanism combined with a reservoir for use in connection with my improved fuel or gasoline feeding means.

10 In Figure 1 of the drawings I have shown an embodiment of my invention applied as a fuel or gasoline feed in connection with a motor vehicle, the motive power of which is an internal combustion engine 9 to which 15 is connected a carburetor 10 by a manifold 11, and a fuel or gasoline supply tank 12 located at the rear of the vehicle at a point below the carburetor, with my improved means (designated in a general way by P)

20 to draw the fuel from the tank and deliver it to the carburetor of the intake of the engine in position between said tank and carburetor, the tank being connected thereto by a pipe 13 and the carburetor by a pipe 25 14; said means to draw fuel from the tank and deliver it to the carburetor is connected by a pipe 15 to the combustion chamber of the engine, such as the opening for the priming cup for the engine, as shown at 16.

30 The means to draw and deliver the fuel from the tank to the carburetor or engine is operable by the varying pressures in the combustion chamber of the engine, such as during the power and compression strokes, 35 or the suction and exhaust strokes, of the engine piston, and in the form thereof shown in Figure 2, includes a high level reservoir 29.

30 The reservoir consists of a cylindrical sheet metal receptacle, in which the pumping mechanism is axially located, said reservoir having an outlet 34 to which the pipe 14 leading to the carburetor is connected, and open at the top with the upper end 45 flaring outward as shown at 35. The reservoir is closed by a cover 36 having an annular flange 37 to engage within the flaring portion 35. The cover has a central opening through which the cylinder 17 extends and the cover flange 37 is caused to forcibly engage the flaring end 35 of the reservoir to prevent leakage by the splashing of the fuel in the reservoir by the screw closure or cap 21 on cylinder 17. 50 Thus the pump cylinder serves somewhat as a centering stud and as a clamping bolt to secure the cover on the reservoir.

55 The pump comprises a cylinder 17 in which there is mounted a reciprocable piston 18, said piston separating the cylinder into a motive chamber 19 and a pump chamber 20. The motive chamber has a port 23 in the removable closure 21 of the cylinder 17 and to the threaded projection 22 of this closure 21 is connected the pipe 15 con-

nected to the engine whereby the motive chamber has a conduit connection with the combustion chamber of the engine cylinder. It will be noted that the port 23 is of extremely small diameter as compared with 70 the volume of the pump chamber but it will be understood that this may be increased or decreased to vary the power and capacity of the pump.

75 The piston 18 has the annular oil groove 39 and carries a packing ring 40 of suitable material, said ring being clamped between the piston and a flanged clamping nut 41 threaded onto a projection 42 of the piston, the flange having a loose fit in the cylinder 80 and providing a recess between said flange and the piston for the engagement of the piston packing for a purpose to be herein-after described. The piston 18 is yieldingly maintained toward the outermost end of the 85 motive chamber by a spring 43, a spring bumper 44 being interposed between the flange of the piston nut 41 and the closure end 21 for the motive chamber to prevent the piston striking against the end of said chamber and making a clicking or knocking noise.

90 The pump chamber 20 has an inlet 24, connected through a coupling and the pipe 13, with the tank 12, the inlet being normally closed by a gravity seated valve 26 opening into and closing outward from the pump chamber 20. The pump chamber has an outlet consisting of a series of circumferentially disposed ports 27 extending diagonally through a flanged portion of the cylinder leading into a reservoir 29. The outlets of the ports are located in a beveled portion 30 forming a seat for a valve 31 to close the ports, said valve being in the form 95 of a sleeve slidably mounted upon the cylinder 17 and having a laterally flaring portion to correspond with the beveled portion 30. The valve opens into and closes outward from the reservoir and is normally maintained yieldingly closed when the liquid level in the reservoir is below a predetermined level by the weight of a float 32 embracing the cylinder 17 and movable longitudinally thereof and an intermediate 100 spring 33 fixed, as by soldering, to the float and valve. A port 38 of small area may be provided to permit of the escape of air from 105 and entrance of air to the reservoir.

110 In the operation of the pumping mechanism during the compression strokes of the piston of the engine due to the connection 115 of the motive chamber of the cylinder 17, with the combustion chamber of the engine cylinder, such pressure will be exerted 120 on the end of the piston nut 41, a portion of such pressure due to the loose fit of the nut flange entering the space between the flange and piston proper expanding the 125 packing 40 and moving the piston against 130

the action of the spring 43, the expansion of the packing ring also preventing the passage of such pressure to the pump chamber. This movement of the piston will unseat the valve 31 to open communication between the pump chamber and the reservoir. During the suction strokes of the engine piston with the consequent reduction of the pressure in the connection 15 and in the motive chamber the spring 43 will move the piston toward the outer end of the motive chamber, the valve 31 having automatically seated by spring 33 such movement of the piston 18 will create a vacuum in the pump chamber unseating the valve 26 and drawing the fuel from the tank 12 through the connection 13 thereof with the pump chamber into the latter. This latter movement of the piston 18 may also be facilitated during the suction stroke of the piston of the engine by the creation of a vacuum in the motive chamber. The pipe 14 leading to the carburetor is connected to the reservoir 29 and the fuel from the reservoir to the carburetor is fed by gravity through said pipe. If used for feeding gasoline to the carburetor on an automobile it would be extremely difficult to proportion the parts so that the continuous operation of the pumping mechanism would not flood the reservoir 29 and to control the fuel level therein the float 32 is provided. As the fuel level in the reservoir rises the buoyancy of the float will cause it to rise and move upward. This motion may be used to control the pump in any desired way. As shown in Figure 2, the float being connected through the spring 33 with valve 31, will lift and unseat the valve 31 maintaining the valve open until the fuel level is lowered, the movement of the piston 18 while the valve 31 is open alternately drawing the fuel from and discharging it into the reservoir until such time as the fuel level permits the float to again assume a position with the valve 31 closed.

It will be noted that the piston 18 at all times shuts off communication between the combustion chamber of the engine cylinder and the tank, and that communication between the intake of the engine and the tank is shut off from the reservoir by the valves 26 and 31 for the inlet and outlet of the pump chamber, and that communication between the tank and intake of the engine is only during the operation of the pumping mechanism.

The reciprocation of the piston 18 synchronizes with the suction and compression strokes of the engine piston, and the stroke of the piston 18 is regulated in accordance with the pressure in the engine cylinder. For instance, should the throttle valve for the fuel intake of the engine be closed with consequent low pressures in the engine cyl-

inder there will be a low pressure in the motive chamber of the cylinder 17 and a short motion or stroke of the piston 18, and as the throttle valve for the engine intake is opened with the consequent increase of pressures in the engine cylinder, there will be a corresponding increase of the pressures in the motive chamber of the cylinder 17 and a longer stroke imparted to the piston 18.

It will be evident, however, that a spring which is yielding enough to permit the above described operation of the piston under close-throttle, low-pressure conditions will function somewhat differently when the engine is operating at high speed. This is because at high speeds, there is more work to be done by the spring actuated stroke of the piston and there is much less time to do it in. Hence the return stroke may be cut short before the piston gets back to initial position.

Moreover, while the extreme constriction of the inlet passage, as shown in the drawings, serves to moderate on the pump piston, the violence of the engine explosions, it also tends to average up the low pressures as well as to average down the high pressures, and this tendency becomes more pronounced with increasing speeds of the engine. Hence though the engine pressures continue alternating from pronounced vacuum to high pressure even at high speeds, the pressures on the pump piston become pulsating, that is, they are above atmosphere even during the vacuum strokes of the engine. This pulsating excess pressure at high speeds tends to force the pump piston toward the spring thereby compressing the spring until a position is reached where the spring is under a continuous minimum compression equal to the continuous minimum pressure in the motive chamber.

The piston continues to reciprocate in response to the variations of pressure, and the length of the stroke may be approximately the same or may be less, but the range of the stroke is shifted enough to make the spring return strokes more powerful and therefore quicker acting.

Making the spring 43 of great length and providing a long clearance or pumping space in the cylinder, as shown in the drawings, affords a considerable range for the above described shift of position of the stroke of the piston and corresponding increase of spring stiffness. It is one good method of rendering the device automatically self-accommodating for the wide range of alternating and pulsating pressures due to the constricted inlet during the widely varying speeds practically necessary in the operation of automobile and similar internal combustion engines. For a wide range of speeds the length of the stroke will be determined by the pulsating differences of

pressure during each cycle of explosion, exhaust, suction and compression in the engine, independently of the amounts of said pressures, changes in the amounts being taken care of by the automatic shift of the position of the stroke to the extent necessary to get a counterbalancing back pressure of the spring.

The spring 44 on the opposite end of the piston, is of shorter length and shorter range of action than spring 43. It functions only when conditions are such as to permit complete return stroke of the piston on each suction stroke of the engine and this, as will be evident, is at the lower engine speeds and pressures, particularly at times when the speeds and pressures are low enough for establishing a vacuum, or below-atmosphere, pressure in the motive chamber of the pump during each suction stroke of the engine. At such times the spring 44 is compressed by the suction stroke of the piston. Then, as soon as the suction is relieved, the expansion of spring 44 initiates and assists the subsequent expansion stroke. In this way the short spring 44 acts during times of alternating suction and pressure on the piston, in a manner somewhat analogous to the action of spring 44 during times of continuous pulsating pressure.

While the float controlled inlet shown herein is one means for governing the pumping of the liquid, it will be evident that the advantageous features of construction of the reservoir and arrangement of pump cylinder as well as the liquid intake and motive pressure inlet may be utilized where governing of the pump is not desired, or where other methods of governing are employed, as for instance, those shown in my said prior application. It is to the former features not specifically claimed in my prior application that the claims of this application are particularly directed.

It will be noted that in the specific governing arrangement shown herein the float 32, spring 33 and outlet valve 31 are means whereby the pump is rendered first ineffective and then inoperative, by gradual lifting of the outlet valve out of range of the outlet passages so the float rises to the uppermost position. Conversely as the liquid is drawn off and the level lowers, the valve seats upon the pump outlets and presses more and more heavily thereon until, in full normal operation, the entire weight of the float may rest upon the valve. Thus in normal operation the outlet will be of much higher resistance to outflow of fluid than the inlet is to inflow. The inlet is of relatively large cross section and has only a free, gravity-seated ball as the check valve therefor. The gravity seated ball is preferred because it is a simple and very effective means of getting the quick, free, low-resistance opening of the inlet

which is very desirable at all times and particularly so, when the supply pipe is empty and the gasoline must be lifted by first pumping air. But the ball form and the absence of spring pressure which gives the quick, free, low-resistance opening, tend to make it slow closing. This is no great disadvantage when the reservoir is full and efficiency of pumping is unnecessary, but when the reservoir is low or the engine operating at very high speed, so that efficient pumping is necessary, slow closing of the inlet valve would permit objectionable slip or backflow of liquid to the tank. In this situation, the back-pressure and high resistance to outflow of liquid due to the pressure on outlet valve 33, is of great importance. With such back-pressure on the outlet, the high speed movement of the piston under the explosive pressure from the engine, takes effect on incompressible liquid and instantly piles up a sufficient back pressure on the inlet valve to force it tight down on its seat at the very beginning of the expelling stroke of the piston.

I claim:

1. A combined reservoir and pump including a vessel adapted to be secured in upright position, and a tubular member including a pump barrel, secured in vertical position in said vessel, a piston in said pump barrel having an upper portion adapted for actuation by fluid pressure and a lower portion formed as a pump piston, the intake of said pump being through the bottom of said tubular member, the discharge through an intermediate portion and the inlet for the pressure medium operating said piston being through the top of said tubular member.

2. Apparatus of the class described, comprising a vessel, a closure for the open end of said vessel, a cylindrical tube rigidly secured to the vessel and projecting outside the vessel and closure at both ends, a double headed piston in said tube, a member screw threaded on the exterior projecting portion of said tube to tension said parts in clamping relation with the tube serving as the tension member of the clamp, a pipe connecting the upper end of said tube with a source of alternating fluid pressure, a liquid supply conduit opening vertically into the lower end of said tube, and an upwardly opening, gravity-seated inlet valve for said conduit.

3. A combined reservoir and pump including a vessel adapted to be secured in upright position, a closure for said vessel, a tubular member secured in vertical position and having passages extending through the bottom and top of said vessel, a piston in said tubular member dividing the same into an upper motive power chamber and a lower pump chamber, the intake of said pump be-

ing through said bottom passage and the inlet for the pressure medium being through the said top passage.

4. A combined reservoir and pump including a vessel adapted to be secured in upright position, a closure for said vessel, a tubular member secured in vertical position in said vessel and having inlet passages from the exterior through its upper and lower end portions respectively, a combined motor and pump element actuated by pressure applied through the upper passage, the intake of said pump being through said bottom passage and the discharge being through an intermediate outlet into said vessel.

5. A combined reservoir and pump including a vessel adapted to be secured in upright position, a closure for said vessel, a tubular member secured in vertical position in said vessel and having inlet passages from the exterior through its upper and lower end portions respectively, a combined motor and pump piston actuated by pressure applied through the upper inlet passage and a spring in the pump chamber; the intake of said pump being through said bottom passage and the discharge being through an intermediate outlet into said vessel, the lower end of said tubular member being rigidly secured through the bottom of said vessel and the upper end projecting through said closure, together with an exterior member screwed on said tubular member to clamp said closure on said vessel.

35 6. In fuel feeding means for internal combustion engines, the combination with an internal combustion engine and a liquid fuel tank, of a reservoir interposed between the tank and engine connected to the intake of the latter; a cylinder centrally of said reservoir; a piston to reciprocate in said cylinder and separating the cylinder into a motive chamber having a port at all times open to the engine cylinder, and a pump chamber; a valve controlled inlet to the pump chamber leading from the tank; outlet ports in the lateral wall of the pump chamber to the reservoir; and a non-return valve adapted to check reverse flow of liquid through said outlet ports when the inlet valve is open.

7. In liquid feeding means for internal combustion engines, the combination with an internal combustion engine and a liquid fuel tank, of a reservoir interposed between the tank and engine connected to the intake of the latter; a cylinder centrally of said reservoir; a piston to reciprocate in said cylinder and separating the cylinder into a motive chamber having a port at all times open to the engine cylinder and a pump chamber; a spring in the pump chamber yieldingly pressing said piston toward said port; a valve controlled inlet to the pump chamber leading from the tank; outlet ports

in the lateral wall of the pump chamber to the reservoir; and a non-return valve adapted to check reverse flow of liquid through said outlet ports during the lifting strokes of said piston.

8. In liquid feeding means for internal combustion engines, the combination with an internal combustion engine and a liquid fuel tank, of a cylindrical reservoir interposed between the tank and engine connected to the intake of the latter; a cylinder arranged axially of said reservoir; a piston to reciprocate in said cylinder and separating the cylinder into a motive chamber having a port at all times open to the engine cylinder and a pump chamber; a valve controlled inlet to the pump chamber leading from the tank; symmetrically spaced outlet ports in the lateral wall of the pump chamber to the reservoir, and a valve adapted to check reverse flow of liquid through said outlet ports.

9. In fuel feeding means for internal combustion engines, the combination with an internal combustion engine and a liquid fuel tank, of a cylindrical reservoir interposed between the tank and engine connected to the intake of the engine; a cylinder arranged axially of said reservoir; a piston to reciprocate in said cylinder and separating the cylinder into a motive chamber having a port at all times open to the engine cylinder and a pump chamber; a valve controlled inlet to the pump chamber leading from the tank; outlet ports in the lateral wall of the pump chamber to the reservoir; and a valve adapted to check reverse flow of liquid through said outlet ports.

10. A combined reservoir and pump for an internal combustion engine, including a vessel adapted to be secured in upright position, a tubular member formed with a pump chamber secured in vertical position, in fixed relation to said vessel, a reciprocating pumping element in operative relation to the upper end of said tubular member for applying alternate suction and pressure to said chamber; means for continuously reciprocating said pump element including a conduit leading to the upper portion of said tubular element from the combustion space in a cylinder of said engine; a conduit from a source of liquid supply, opening into the bottom portion of said pump chamber; a non-return valve for permitting flow of the liquid into said pump chamber and preventing reverse flow; a discharge outlet from said pump chamber into said vessel and means for opposing back flow of liquid into said outlet when said non-return valve is open.

11. A combined reservoir and pump for an internal combustion engine, including a vessel adapted to be secured in upright position, a tubular member formed with a

pump chamber secured in vertical position, in fixed relation to said vessel, a reciprocating pumping element in operative relation to the upper end of said tubular member for applying alternate suction and pressure to said chamber; means for reciprocating said pump element including a conduit leading to said reciprocating pump element from the combustion space in a cylinder of said engine and a conduit from a source of liquid supply, opening upward into the bottom of said pumping chamber; a normally seated ball valve adapted to be lifted against gravity by suction toward said pump chamber; a discharge outlet from said pump chamber into said vessel and means for opposing back flow of liquid through said outlet when said ball valve is lifted.

12. A combined reservoir and pump including a vessel adapted to be secured in upright position, and a tubular member including a pump barrel, secured in vertical position in said vessel, a piston in said pump barrel dividing it into an upper motive chamber and a lower pump chamber, the intake of said pump chamber being through a gravity seated valve at the bottom of said tubular member, the outlet being through an intermediate portion, and the inlet for motive fluid to the piston being through the top of said tubular member.

Signed at New York city in the county of New York and State of New York this 18 day of March, 1920.

WILLARD I. TWOMBLY.
